(57) **CLAIM**

The ornamental design for a display screen or portion thereof with animated graphical user interface, as shown and described.

DESCRIPTION

FIG. 1 is a front view of a first embodiment of a display screen or portion thereof with animated graphical user

interface showing a first image in the sequence showing our new design;

FIG. 2 is a second image thereof;

FIG. 3 is a third image thereof;

FIG. 4 is a front view of a second embodiment of a display screen or portion thereof with animated graphical user interface showing a first image in the sequence showing our new design;

FIG. 5 is a second image thereof;

FIG. 6 is a third image thereof;

FIG. 7 is a front view of a third embodiment of a display screen or portion thereof with animated graphical user interface showing a first image in the sequence showing our new design;

FIG. 8 is a second image thereof;

FIG. 9 is a third image thereof;

FIG. 10 is a front view of a fourth embodiment of a display screen or portion thereof with animated graphical user interface showing a first image in the sequence showing our new design;

FIG. 11 is a second image thereof;

FIG. 12 is a third image thereof;

FIG. 13 is a front view of a fifth embodiment of a display screen or portion thereof with animated graphical user interface showing a first image in the sequence showing our new design;

FIG. 14 is a second image thereof;

FIG. 15 is a third image thereof;

FIG. 16 is a front view of a sixth embodiment of a display screen or portion thereof with animated graphical user interface showing a first image in the sequence showing our new design;

FIG. 17 is a second image thereof;

FIG. 18 is a third image thereof;

FIG. 19 is a front view of a seventh embodiment of a display screen or portion thereof with animated graphical user interface showing a first image in the sequence showing our new design;

(Continued)

FIG. 20 is a second image thereof; and, FIG. 21 is a third image thereof.

The dash-dot broken lines in the drawings illustrate the display screen or portion thereof and form no part of the claimed design. The remaining dashed broken lines, regardless of their thickness, illustrate portions of the graphical user interface that form no part of the claimed design.

The appearance of the animated graphical user interface sequentially transitions between the images shown in FIGS. 1-3, between the images shown in FIGS. 4-6, between the images shown in FIGS. 7-9, between the images shown in FIGS. 10-12, between the images shown in FIGS. 13-15, between the images shown in FIGS. 16-18, and between the images shown in FIGS. 19-21. The process or period in which one image transitions to another forms no part of the claimed design.

The background of the graphical user interface of FIG. 2 and the background of the graphical user interface of FIG. 3 are shown as being blurred. Elements in each of the blurred backgrounds of FIGS. 2-3 correspond to claimed elements and environmental subject matter appearing in the same portion of the graphical user interface in FIG. 1 and form no part of the claimed design. The background of the graphical user interface of FIG. 5 and the background of the graphical user interface of FIG. 6 are shown as being blurred. Elements in each of the blurred backgrounds of FIGS. 5-6 correspond to claimed elements and environmental subject matter appearing in the same portion of the graphical user interface in FIG. 4 and form no part of the claimed design. The background of the graphical user interface of FIG. 8 and the background of the graphical user interface of FIG. 9 are shown as being blurred. Elements in each of the blurred backgrounds of FIGS. 8-9 correspond to claimed elements and environmental subject matter appearing in the same portion of the graphical user interface in FIG. 7 and form no part of the claimed design. The background of the graphical user interface of FIG. 11 and the background of the graphical user interface of FIG. 12 are shown as being blurred. Elements in each of the blurred backgrounds of FIGS. 11-12 correspond to claimed elements and environmental subject matter appearing in the same portion of the graphical user interface in FIG. 10 and form no part of the claimed design. The background of the graphical user interface of FIG. 14 and the background of the graphical user interface of FIG. 15 are shown as being blurred. Elements in each of the

blurred backgrounds of FIGS. 14-15 correspond to claimed elements and environmental subject matter appearing in the same portion of the graphical user interface in FIG. 13 and form no part of the claimed design. The background of the graphical user interface of FIG. 17 and the background of the graphical user interface of FIG. 18 are shown as being blurred. Elements in each of the blurred backgrounds of FIGS. 17-18 correspond to claimed elements and environmental subject matter appearing in the same portion of the graphical user interface in FIG. 16 and form no part of the claimed design. The background of the graphical user interface of FIG. 20 and the background of the graphical user interface of FIG. 21 are shown as being blurred. Elements in each of the blurred backgrounds of FIGS. 20-21 correspond to claimed elements and environmental subject matter appearing in the same portion of the graphical user interface in FIG. 19 and form no part of the claimed design.
